UNITED STATES PATENT OFFICE.

RALPH P. BARNES, OF SCHENECTADY, NEW YORK.

ELECTRICALLY-CONTROLLED RELEASING DEVICE.

No. 876,036.

Specification of Letters Patent.

Patented Jan. 7, 1908.

Application filed April 1, 1907. Serial No. 365,772.

To all whom it may concern:

Be it known that I, RALPH P. BARNES, a citizen of the United States, residing at Schenectady, county of Schenectady, State 5 of New York, have invented certain new and useful Improvements in Electrically - Controlled Releasing Devices, of which the following is a specification.

My invention relates to that class of devices which are adapted to be controlled from a distance to release horses from their stalls, unlock doors, or the like; such devices either serving as the securing means for the thing to be released or else operating simply 15 to control some other securing means; and the object of my invention is to produce such a device which shall be simple and compact in construction, neat in appearance, and quick and reliable in operation.

20 To the above end my invention comprises a novel construction and arrangement of parts to be hereinafter described and pointed out with particularity in the appended claims.

In the accompanying drawing, Figure 1 25 is a side elevation of a panel having mounted thereon a device constructed in accordance with a preferred form of my invention, the parts being in locking positions; Fig. 2 is a view similar to Fig. 1, the parts being, however, in their releasing positions; Fig. 3 is a 30 view looking toward the left in Fig. 2; and Fig. 4 is a view looking upward in Fig. 1.

Referring to the drawing, 1 indicates a flat metal bracket mounted upon a panel 2 35 of wood or other material.

3 is a bolt slidably mounted in guides 4 and 5 secured to the bracket. The bolt may be operated to set the device by means of the handle 3^a.

40 6 and 7 are tension springs arranged on opposite sides of the bolt and connected at one end to a cross-bar 8 carried at the inner end of the bolt. At their other ends the springs are secured to the panel. When free to do 45 so, the springs draw the bolt inward until it rests upon a stop 9 secured to or forming part of the bracket. To the outer end of the bolt is attached one end of a chain or cable 10 which is connected in any suitable way to 50 the lock or catch which is to be released upon the operation of the bolt.

I prefer to control the locking of the bolt in a position wherein it is out of engagement with the stop by means of an electromagnet 55 which may readily be energized or deener-

gized by pressing a push-button or opening or closing a switch in any manner at a point which may be far removed from the panel. Therefore I have devised an arrangement of parts whereby the bolt may be securely held out of engagement with the stop against the tension of the strong actuating springs by means of a small electromagnet, while at the same time a quick and sure release is effected upon the operation of the controlling switch. An arrangement of this character which has operated very satisfactorily in practice is shown on the drawing, 11 being the magnet which is illustrated as being double and having its two cores rigidly secured at one end to a flange 12 on the bracket. Thus, when the bracket is made of magnetic material, it serves not only as the supporting means for the magnet but also as part of the magnetic circuit thereof. The magnet is 75 preferably, but not necessarily, arranged to operate on closed circuit and this is the form in which it is illustrated. In Fig. 1 I have shown conventionally a battery 13 and a normally closed switch 14 which respectively supply the current and control the circuit through the magnet.

15 is the armature of the magnet and 16 is a spring which tends to draw it out of the field of the magnet.

17 is a hook pivoted at 18 on the guide plate 4 and engaging normally with a pin 19 carried by the bolt and having a loose sleeve 20 surrounding it. One end of the hook is pivoted to one end of a toggle 21 which is in turn pivotally secured at its other end, as at 22, to the bracket. When the toggle is straightened as shown in Fig. 1, the hook is locked in the position wherein it engages with the sleeved pin on the bolt to hold the bolt in its outermost position against the tension of the springs. A bell-crank lever 23 is pivotally secured to the bracket, as at 24, at one side of the toggle. One arm of the lever extends toward the toggle and has a cam 25 which lies directly beneath the joint of the toggle. When the lever is oscillated, the cam engages with the toggle and presses the center slightly out of alignment with the pivots at the ends. Thereupon, the rigid support for the hook 105 being removed, and the hook being slightly oscillated, the actuating springs for the bolt, operating through the bolt, force the hook laterally and completely out of engagement with the sleeved pin. The bolt is now free 110

and is drawn inward until it strikes against the stop. This releases the horse or the door or whatever is controlled by the chain or cable. In order that the cam may be actuated with considerable power, a spring 26 is secured between the bell crank lever and the bracket and forces the cam into its tripping position when free to do so.

The magnet controls the hook, through the mechanism just described, by means of a lug 27 on the armature; this lug normally resting under a lug 28 on the free arm of the bell crank lever and holding the lever in such position that the cam allows the toggle to be straightened. The lugs 27 and 28 register only when the armature is drawn against the end of the magnet, so that, when the magnet is deenergized and the spring 16 draws the armature outward, the lug 27 is moved from under the lug on the lever and the actuating spring for the lever becomes free to oscillate it and thereby break the joint of the toggle; whereupon the bolt is released and withdrawn in the manner previously described.

To set the device, the lever 23 is moved from the position indicated in Fig. 2 to the normal position shown in Fig. 1. If the switch 14 is in its normal position, so that the magnet is energized, the lever will be locked in the position to which it has been moved. The bolt 3 may then be actuated against the tension of the springs, and the toggle lever straightened until the hooks 17 and the member 19 on the bolt are brought into locking engagement with each other so as to hold the bolt in the position shown in Fig. 1. The device is now ready to operate in the manner previously described upon the deenergization of the magnet.

It will be seen that by reason of the peculiar construction and arrangement of parts illustrated and described, a neat, compact, powerful and reliable releasing device is pro-

duced without necessitating the use of any but the smallest of magnets.

45

What I claim as new and desire to secure by Letters Patent of the United States, is,—

1. A releasing device consisting of a bolt, a spring for actuating the bolt, a hook pivoted intermediate its ends and engaging the bolt to hold the same against the actuating spring therefor, a toggle arranged at one side of the hook and having its ends pivoted respectively to one end of the hook and to a fixed support so as to form a strut to lock the hook in place when the two members of the toggle are brought into alinement with each other, a pivoted cam lever arranged to engage with the toggle and break the joint thereof so as to trip the hook, an actuating spring for the cam lever, an electromagnet, and an armature for said electromagnet having a shoulder for holding the cam lever in its inoperative position against the tension of its actuating spring. 65

2. A releasing device consisting of a flat bracket, a spring actuated bolt slidingly mounted on said bracket, a locking hook for said bolt pivoted to said bracket, a toggle pivoted at one end to the hook and at the other end to the bracket, the toggle when straightened being substantially at right angles to the stem of the hook, a cam lever pivoted to the bracket at one side of the toggle, a spring for operating said cam lever to break the joint of the toggle, and an electromagnet rigidly supported by the bracket for normally holding said cam lever in an inoperative position against the tension of the operating spring. 75

In witness whereof, I have hereunto set my hand this 30th day of March, 1907.
